FLUSH TANK VALVE

Fred L. Suitt, Durham, N. C.

Application February 7, 1939, Serial No. 255,141

5 Claims.

(CL 4—62)

The present invention relates to valves for flush tanks and has for its primary object to provide an automatic gravity actuated valve for positively closing the discharge opening in the flush tank and providing a dash-pot valve controlling mechanism adapted to retard closing movement of the valve.

A further object of the present invention is to provide a dash-pot controlling mechanism for a valve of the above character in which a cylinder is provided having a confined fluid therein and within which a valved piston is arranged to retard the closing movement of the valve and by employing the use of a confined fluid in the cylinder it is possible to use a non-freezing liquid to insure proper controlling movement of the valve at all temperatures.

A still further object is to provide a device of this character of simple and practical construction, which is efficient and reliable in performance, relatively inexpensive to manufacture and install in operative position and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a side elevational view with parts broken away and shown in section.

Figure 2 is a top plan view.

Figure 3 is a transverse sectional view taken substantially on a line 3—3 of Figure 1.

Figure 4 is a vertical sectional view through the dash-pot, and

Figure 5 is a fragmentary vertical sectional view of the swivel connection for the valve stem.

Referring now to the drawings in detail, the numeral 5 designates the bottom of a flush tank having the discharge pipe 6 threaded therethrough and secured in position by the lock nut 7. The upper end of the pipe 6 is formed into a valve cage 8 having the tapered valve seat 9 at the bottom portion thereof, the walls of the cage above the valve seat being provided with vertically extending openings 10.

The overflow pipe 11 rises vertically from the connection 12 which communicates with the discharge pipe below the valve seat 9.

Cooperating with the valve seat is the valve 13 having the conical composition valve disk 14 secured in position by the nut 15, the disk 14 hav-

ing its side edges cooperating with the valve seat 9.

Rising from the valve is the valve stem 16 which has a working fit in the vertically extending tubular guide 17 which rises from the top 18 secured in the upper portion of the valve cage 8 by the set screws 19. The upper end of the valve stem 16 is recessed as shown at 20 and within which is inserted the flanged lower end 21 of a rod 22, the rod being secured in position 10 within the recess by a threaded plug 23 to provide for the free rotary movement between the valve stem and the rod. The plug 23 is secured against accidental displacement by a set screw 24.

A cylinder 25 is cast integrally with the guide 17 by means of the integrally formed lugs 26, the cylinder extending vertically in parallel relation with respect to the guide, and is closed at its lower end and provided with a threaded cap 27 at its upper end. A piston 28 has a 20 working fit in the cylinder, the piston being provided with passages 29 extending therethrough, said passages being controlled by a ball check valve 30 adapted to seat upwardly against the valve seat 31 in the lower portion of the piston 25 to close communication therethrough by a downward movement of the piston. The valve 30 is retained against accidental displacement by a rod 32 extending transversely across the lower end of one of the passages in the piston. A rod 33 extends upwardly from the piston through an opening in the cap 27 and is connected to the rod 22 by a cross head 34, the end of the cross head being split as at 35 and secured in clamping relation against the rod 22 at one end and the rod 33 at the other end by means of set screws 36, by means of which it will be apparent that the cross head may be adjustably secured in position.

To the cross head is secured a bracket 37 by 40 means of which the manipulating lever of the flush tank may be adjustably secured in the openings 38.

A by-pass 39 connects the upper and lower portions of the cylinder 25, the lower end of the by-pass being formed with a valve seat 40 with which a needle valve 41 cooperates, the needle valve being threaded through the wall of the cylinder and provided at its outer end with a manipulating head 42.

In the operation of the device a suitable fluid is placed in the cylinder 25 and upon the opening of the valve 13 the piston 28 will simultaneously be moved upwardly, the passages 29 in the piston permitting unrestricted upward movement 55

of the piston. It will be apparent, however, that the closing movement of the valve 13 will be retarded as the downward movement of the piston 28 will cause the ball check valve 30 to seat against the valve seat 31 thereby closing communication through the piston, the needle valve 41 regulating the passage of the liquid from the lower portion of the cylinder 25 through the by-pass 39 into the upper portion thereof, where-
10 by to regulate the closing movement of the valve 13.

It will be understood that the valve 13 is weighted sufficiently to cause a gravitating closing movement thereof.

15 It is believed the details of construction and manner of operation of the device will be readily understood from the foregoing without further detailed explanation.

Having thus described the invention, what I
20 claim is:

1. A valve for flush tanks comprising a gravity actuated valve member adapted to control discharge of water from the tank and a dash-pot mechanism provided with a confined fluid and
25 operatively connected to the valve for retarding movement of the valve.

2. A valve for flush tanks comprising a gravity actuated valve member adapted to control discharge of water from the tank and a dash-pot
30 mechanism operatively connected to the valve for retarding movement of the valve, said dash-pot mechanism comprising a cylinder, a confined fluid therein and a valved piston working in the cylinder.

35 3. A valve for flush tanks comprising a gravity actuated valve member adapted to control discharge of water from the tank and a dash-pot

mechanism operatively connected to the valve for retarding movement of the valve, said dash-pot mechanism comprising a cylinder having a confined fluid therein, a by-pass connecting the upper and lower ends of the cylinder and a valved piston working in the cylinder adapted for free upward movement and retarded in its downward movement to delay closing of the valve member.

4. A valve for flush tanks comprising a gravity actuated valve member, a stem rising therefrom, a cylinder having a piston working therein, a stem rising from the piston, a cross head connecting the valve stem and piston stem for uniform movement, a by-pass connecting the upper and lower ends of the cylinder, a confined fluid in the cylinder, a passage through the piston and a valve in the piston adapted to close the passage upon a downward movement of the piston and providing free communication between the upper and lower portions of the cylinder upon upward movement thereof.

5. A valve for flush tanks comprising a gravity actuated valve member, a stem rising therefrom, a cylinder having a piston working therein, a stem rising from the piston, a cross head connecting the valve stem and piston stem for uniform movement, a by-pass connecting the upper and lower ends of the cylinder, a confined fluid in the cylinder, a passage through the piston and a valve in the piston adapted to close the passage upon a downward movement of the piston and providing free communication between the upper and lower portions of the cylinder upon upward movement thereof and a manually ad-
35 justable valve controlling the by-pass.

FRED L. SUITT.
